SCREEN

Paul Tartaglia, Albany, N. Y.

Application April 13, 1943, Serial No. 482,914

2 Claims. (Cl. 160—217)

This invention relates to new and useful improvements in screens and more particularly to window or door screens.

The principal object of the present invention is to provide a screen which can be easily inserted in position without the employment of any fixtures for placement on the window frame or door frame in which the screen is to be inserted.

Another important object of the invention is to provide a window screen which can be readily inserted in the guideway of the usual upper window sash, thus dispensing with the necessity of a full length screen.

Other important objects and advantages of the invention will become apparent to the reader of the following description.

In the drawings—

Figure 1 is a fragmentary elevational view showing a window equipped with the improved screen.

Figure 2 is a section on the line 2—2 of Figure 1.

Figure 3 is a sectional view substantially on the same plane as Figure 1, but showing the screen about to be removed.

Figure 4 is a fragmentary detailed sectional view showing a slightly modified form of the invention.

Figure 5 is a fragmentary detailed sectional view showing another modification of the invention.

Referring to the drawings wherein like numerals designate like parts, it can be seen that numeral 5 generally refers to a window frame, the same including an upper sash 6, a sill 7, stiles 8, 8, these stiles being provided with runners 9 to define guideways for the upper and lower sashes.

Numerical 10 generally refers to the improved screen which comprises a rectangular-shaped frame 11, one side rail of which is divided into a pair of sections 12, 13, the section 12 has a tongue 14 which fits into a rabbeted portion 15 of the section 13, and these sections are hinged together as at 16. It is preferable that the stile side of the section 13 be beveled as denoted by numeral 17.

The frame 11 is internally rabbeted to receive the edge portion of a screen 18 and retaining strips 19.

Detents 20, 21 are provided for the screen, each detent consisting of a swingable latch member fulcrumed as at 21 and having a foot 22 at

one end and a finger grip 23 at its opposite end. The foot 22 serves as a filler, filling up the space between the frame and holding the screen frame firmly against the intermediate guideway strips 9.

5 It can be seen that when the window screen is to be removed, the detents 20 are swung to vertical position as shown in Figure 3 and the section 13 of the sectional side rail swung to the position shown in Figure 3. The screen can be 10 turned and brought inwardly through the window frame and, of course, the same course can be followed in placing the screen in position under the upper sash 6.

Figure 4 shows a window screen frame 10a which has one side rail divided into a pair of sections 12a, 13a, hingedly connected together as at 16a. The sections 12a and 13a have plain opposed sides in contrast to the interlapping portion of the form of the invention shown in Figures 2 and 3.

Figure 5 shows a slightly modified form of the invention in that the window screen frame which is here referred to by reference character 10b is not rabbeted to accommodate a screen sheet as in Figures 2, 3 and 4, but this sheet which is here denoted by reference character 18a is secured directly to the outside of the frame 10b with the assistance of retaining strips 19a.

While the foregoing specification sets forth the invention in specific terms, it is to be understood that numerous changes in the shape, size and materials may be resorted to without departing from the spirit and scope of the invention as claimed hereinafter.

35 Having described the invention, what is claimed as new is:

1. A screen of the character described comprising a frame, a screen strip secured to the frame, one rail of the frame being divided into 40 a pair of sections one being hingedly attached to the other.

2. A window screen comprising a frame, a screen strip secured in said frame, the frame including a side rail divided into a pair of sections, one of the sections having a rabbeted outer side forming a longitudinal tongue on one face of the section and a groove extending along said tongue, the other section being hinged to the one section within said groove and having a rabbeted longitudinal corner interfitting with said tongue.

PAUL TARTAGLIA.
